CLAIM

The ornamental design for a pump for analyzing machine of liquid chromatograph, as shown.

DESCRIPTION

FIG. 1 is a front, top and right side perspective view of a pump for analyzing machine of liquid chromatograph showing our new design;

FIG. 2 is a front elevational view thereof;

FIG. 3 is a rear elevational view thereof;

FIG. 4 is a right side view thereof;

FIG. 5 is a top plan view thereof;

FIG. 6 is a bottom plan view thereof; and,

FIG. 7 is a left side view thereof.

*FIG. 1**FIG. 2**FIG. 3**FIG. 4**FIG. 5**FIG. 6**FIG. 7*
